E. JOHNSON.

SAW SETTING MACHINE.

APPLICATION FILED DEC. 11, 1911.

1,029,614.

Patented June 18, 1912.

UNITED STATES PATENT OFFICE.

EDWARD JOHNSON, OF HAWTHORN, PENNSYLVANIA, ASSIGNOR OF ONE-HALF TO
JOHN FINKBEINER, OF HAWTHORN, PENNSYLVANIA.

SAW-SETTING MACHINE.

1,029,614.

Specification of Letters Patent. Patented June 18, 1912.

Application filed December 11, 1911. Serial No. 665,032.

To all whom it may concern:

Be it known that I, EDWARD JOHNSON, a citizen of the United States, residing at Hawthorn, in the county of Clarion and 5 State of Pennsylvania, have invented certain new and useful Improvements in Saw-Setting Machines, of which the following is a specification.

The present invention relates to saw setting machines and is specially designed for use in setting the teeth of circular saws.

Among the prominent features of novelty and meritorious objects of the invention is the capability of adjustment of parts of the 15 machine adapting it for use with differing sizes of circular saws; its simplicity of adjustment and operation; its durability, and its comparatively inexpensive cost of production.

20 The invention consists in certain novel features of construction and combinations and arrangements of parts as hereinafter set forth and more distinctly pointed out in the appended claim which forms a part 25 of this specification.

In the accompanying drawings I have illustrated one example of the physical embodiment of my invention constructed according to the best mode I have so far devised for the practical application of the 30 principles.

Referring to the drawings in which like reference characters indicate similar parts throughout the views: Figure 1 is a plan 35 view of the machine constructed according to the principles of the present invention, showing, in dotted lines, a portion of a circular saw. Fig. 2 is a side elevation of Fig. 1, with parts broken away for purpose 40 of clearer illustration. Fig. 3 is a sectional view on line 3—3 of Fig. 2.

In the preferred embodiment of the invention as illustrated in the drawings, the base plate 1 is of usual construction, and is 45 formed with a dove-tail groove 2, between the side bars 3, 3, and is also provided with perforated lugs 4, by means of which, and suitable fastening devices, the machine may be firmly held and supported while its 50 functions are being performed.

Within the groove 2 of the base plate are adapted to be moved, and held, the two blocks 5 and 6. The former, block 5, is the saw support, and for the purpose of 55 supporting a saw, as 7, indicated in dotted

lines, the block is provided with a projection or lug 8 on its upper surface over which the central perforation of the saw is passed, and about which the saw may be turned as on a pivot. At one end, and upon 60 its lower or under side, the block 5 is provided with a dovetail tongue 9, complementary to the groove 2 and slideable therein. In addition to the tongue 9, for holding the block 5 in place I utilize the bolt 10, 65 which is passed through a perforation in the extension 11 of the block 5, and fashioned with a head 12, which as clearly seen in Fig. 3 is complementary to the slot or groove 2 and fits neatly therein. From this 70 description it will be apparent that the block 5 may be moved along the base plate and is guided by the tongue 9 and head 12 in the groove 2, and when moved to adjusted position, the block may be there held 75 by means of the nut 13. The anvil block 6 is also provided with a dovetail tongue, as 14, clamping bolt 15 with its specially shaped head 16 and clamping nut 17, similar to the pivot block 5.

The upper portion of the block 6 is bored out for the reception of a bolt or anvil 18, which is preferably cylindrical in cross section and held in the bore of the block by a pin or key 19, passed through a transverse 85 opening in the block and engaging a groove in the anvil. The upper face of the anvil 18 is of conical formation as indicated at 20 to receive the swaged tooth of the saw, and in order that the latter may be trued thereon. 90

The setting tool comprises a shank 21 fashioned with the head 22 and the reduced extension 23 about which is coiled the spring 24. The shank, extension and spring are incased within the cylindrical recess or bore 95 25 of the block, and this bore is counter-bored as at 26 for the reception of the extension. A recess or groove 21^a is formed in the shank 21 in which is located a portion of the pin or key 19. The engagement of 100 the pin in the groove or recess prevents rotation of the tool, and also holds the tool against outward pressure of the spring. A pair of chambers or recesses are provided in the head, one extending downwardly and the other upwardly from the upper and lower surfaces respectively of the head, and in these recesses are seated the hammer-bolt 27 and the setting-bolt 28, the latter of 105 which is formed with a beveled bottom 29 110

complementary to the conical top 20 of the anvil 18. A pin 30 is conveniently positioned to secure both the bolts 27 and 28 within the head 22, in manner similar to locking the anvil 18.

When it is desired to set the teeth of a saw, the saw is placed upon the supporting block 5 with the lug 8 projecting through the central perforation of the saw, and the 10 teeth of the saw located between the anvil and setting bolt, as shown in dotted lines Fig. 2. With the parts in this position, a blow from a hammer or other tool upon the hammer bolt 27, imparts a blow to the tooth 15 upon the anvil through the medium of the setting tool and its setting bolt 28, and in this manner the tooth is set to proper position. The saw is now turned on the lug 8 as its pivot until the next tooth is centered 20 under the setting bolt *i. e.* the next tooth to be bent downwardly, and the operation is repeated. After the teeth are set at one side of the saw, the saw is turned over and the teeth set on the opposite side as usual. 25 The spring 24 acts as a cushion to take up the shock of the blow of the hammer, and to return the tool to normal position.

To adjust the machine for differing sizes of saws, the two blocks may be moved along

on the base plate and secured in position by 30 means of the clamping nuts 13 and 17. It will be noted that the members 18, 27, and 28 may be taken out and replaced, whenever desirable, to provide against wear, and breakage, and also to utilize a variety of 35 tools, as for instance an anvil 18 may be used, having a top different than the top 20 of the anvil 18. Other changes and alterations are contemplated, as within the scope of the following claim.

Having thus fully described my invention what I claim as new and desire to secure by 40 Letters Patent is:—

The combination with a base plate of an anvil block, and an anvil, a setting tool comprising a spring pressed shank movable within a recess in the block and a head on the shank, and a locking key engaging the anvil and said shank to lock the anvil in place and to prevent dislodgment of the 45 shank.

In testimony whereof I affix my signature in presence of two witnesses.

EDWARD JOHNSON.
